BY

William B. Roberts.

ATTORNEY

UNITED STATES PATENT OFFICE.

FRANK W. BEBERDICK, OF WEST HOBOKEN, NEW JERSEY.

DESIGN FOR A VEST-PATTERN.

SPECIFICATION forming part of Design No. 30,221, dated February 14, 1899.

Application filed November 8, 1898. Serial No. 695,896. Term of patent 14 years.

To all whom it may concern:

Be it known that I, FRANK W. BEBERDICK, a citizen of the United States, residing at West Hoboken, in the county of Hudson and State of New Jersey, have invented and produced a new and original Design for a Vest-Pattern, of which the following is a specification, reference being had to the accompanying drawing, forming part thereof.

10 The drawing represents in plan view a pattern of one side and half of the back of the vest, showing my new design, and it will be understood that the other side and half of the back are the same.

15 As shown in the drawing, the leading or material feature of my design consists in the part A, forming one side and half the front, and the part B, forming half of the back, and in the particular shape or contour given to

20 the upper edge or ends of these parts. From the point a the front edge of the part A extends upwardly and inwardly in a curved line a' to the point a^2 , from whence the edge extends in a slight downward and then up-

25 ward curve to the point a^3 , forming the compound-curved line a^4 , which represents the shoulder-seam of the garment. The point a^3 is located below the point a^2 and considerably above the point a . The lines a^4 and

30 a' , being similarly curved adjacent to their meeting-point a^2 , form a sharp upwardly-projecting point.

The edge of the upper portion of the part A extends downwardly and inwardly from

35 the point a^3 in a curved line to the point C^2 , from which point the said edge extends in substantially a straight line which is slightly inclined downwardly to the point a^5 . From

40 the point a^5 the edge extends downwardly in a slightly-curved line to the point a^6 , which point is located in substantially the same vertical plane as the point a^5 . From the point a^6 the edge extends in a slightly-curved line,

45 which is downwardly inclined to the point a^7 , from which point the edge extends upwardly to the point a in a line which is slightly curved at its upper and lower portions. By

reason of the curvatures given to the edge between the points a a' and a^5 a^6 the distance between the points a^7 a^6 is considerably less 50 than the distance between the points a a^5 , which provides for the proper conformation of the garment to the figure.

The outer edge of the part B extends in a substantially straight line from the point b 55 to the point b' , from whence it extends in a slightly-curved line which is downwardly inclined to the point b^2 . From the point b^2 the edge extends upwardly in a curved line to the point b^3 , which point is on the same horizontal plane as the point a^5 of the part A, while the point b^3 is slightly below the horizontal plane of the point a of the said part A. From the point b^3 the edge of the part B extends upwardly and inwardly in a curved 60 line to the point C^3 , from whence the said edge extends upwardly in a slightly-inclined but substantially straight line to the point b^4 . The point b^4 is located slightly below the horizontal plane of the point a^3 of the part A 65 and is separated therefrom, forming the space b^6 . From the point b^4 the edge of the part B extends upwardly in a sharply-inclined line, which is curved at its upper portion to the point b^5 . The upper edge of the part B extends from the point b^5 in a downward curve 70 to the point b , which point is located slightly below the point b^5 , but slightly above the horizontal plane passing through the point a^2 of the part A.

Having fully described my invention, I claim as new and desire to secure by Letters Patent—

The design for a vest-pattern as herein shown and described.

In testimony that I claim the foregoing as my invention I have signed my name, in presence of the subscribing witnesses, this 5th day of November, 1898.

FRANK W. BEBERDICK.
